CIRCUIT BREAKER

George G. Grissinger, Wilkinsburg, and Ture Lindstrom, Edgewood, Pa., assignors to Westinghouse Electric & Manufacturing Company, East Pittsburgh, Pa., a corporation of Pennsylvania.

Application October 18, 1941, Serial No. 415,617

16 Claims. (Cl. 200—89)

This invention relates to circuit breakers and more particularly to circuit breakers of the type used for controlling light to and moderate power distribution circuits.

An object of the invention is the provision of an improved circuit breaker which is operable in response to overload currents and in response to undervoltage conditions in the circuit controlled by the breaker to automatically interrupt the circuit.

Another object of the invention is the provision of a circuit breaker in which a spring means controlled by a trip device is operative upon the occurrence of predetermined abnormal conditions to cause an automatic opening operation of the breaker and which is also operable to reset the trip device upon opening of the breaker.

Another object of the invention is to provide a circuit breaker with an improved undervoltage trip device in which a spring acts to cause an automatic opening operation of the breaker in response to predetermined abnormal undervoltage conditions, said spring being also operable to restore the trip device to reset position upon opening the contacts.

Another object of the invention is the provision of a circuit breaker having an improved trip device operable in response to predetermined undervoltage conditions to cause an opening operation of the contacts and in which the trip device is automatically reset upon opening of the contacts.

Another object of the invention is the provision of a circuit breaker having a switch member movable to open and close the circuit with a spring operated trip device in which the switch member acts through the spring to reset the trip device upon opening of the breaker and to store tripping energy in the spring upon closing movement of the switch member.

Another object of the invention is the provision of a circuit breaker having a novel trip device comprising a spring means in which energy is stored by the closing movement of the breaker and which is released to cause automatic operation of the breaker mechanism in response to predetermined undervoltage conditions in the circuit.

Another object of the invention is the provision of a circuit breaker having a novel trip device in which a resilient means is connected between a tripping member and a part movable with the movable contact assembly, the tripping member being normally held against tripping movement by an electromagnet which releases the tripping

member in response to predetermined abnormal conditions in the circuit.

Another object of the invention is the provision of the circuit breaker as previously described in which the opening movement of the breaker acts through the resilient means to reset the tripping member.

Another object of the invention is the provision of a circuit breaker as previously described in which the resilient means for tripping the breaker and for resetting the trip member permits overtravel in both directions of the parts to which the resilient means is connected.

Another object of the invention is the provision of a circuit breaker in which the movement of the operating mechanism to open the circuit resets the trip device.

The novel features that are considered characteristic of the invention are set forth in particular in the appended claims. The invention itself, however, both as to structure and operation, together with additional objects and advantages thereof, will be best understood from the following description of one embodiment thereof when read in conjunction with the accompanying drawings, in which:

Figure 1 is a side elevational view of a three-pole circuit breaker embodying the principles of the invention;

Fig. 2 is a vertical sectional view through the center pole of the breaker;

Fig. 3 is an enlarged fragmentary horizontal sectional view of a part of the trip mechanism;

Fig. 4 is an enlarged detail view of the undervoltage trip device shown in tripping position;

Fig. 5 is an enlarged vertical sectional view taken on line V—V of Fig. 1; and

Fig. 6 is an enlarged sectional view taken on the center line of the resilient linkage of the undervoltage trip device.

Referring to Fig. 2 of the drawings, the breaker is provided with an operating mechanism common to all of the poles which is mounted in a U-shaped main frame 16 comprising a pair of frame members 17 rigidly connected by a cross member 19. The frame 16 is mounted on the central portion of a base 11 of insulating material and is secured thereto by means of bolts 21 and 23. The outer ends of the frame members 17 are rigidly connected by a cross member 25.

The bolt 23 extends through the cross member 19 and serves to rigidly secure a connector 27 of conducting material to the cross member and to the base 11. A shaft 29 extending through an opening in the connector 27 and through

openings in the frame members 17 pivotally supports a pair of arms 31 having their free ends integral with a contact arm 30 for the center pole. The contact arms 30 (Fig. 1) for the outer poles are identical with the arm 30 for the center pole but are not provided with arms 31. The contact arms 30 for the outer poles are rigidly secured to a tie bar 67 which extends across all of the poles and which is clamped to the center pole contact arm 30 by means of a split clamp 70 and a screw 71. Rectangular tubes 69 of insulating material between the tie bar 67 and contact arms 30 for the several poles serve to insulate the three movable contact arms and their associated contacts from the tie bar 67.

The movable contact structures and the stationary contacts for the several poles are alike for which reason only the contacts for the center pole will be described. The contact arm 30 for the center pole pivotally carries a main movable contact member 47 and a movable arcing contact member 55. The main contact member 47 is pivoted on a pivot pin 49 supported in projections 51 of the contact arm 30, and the movable arcing contact member 55 is pivoted on a pivot pin 57 supported in projections 59 of the arm 30. The main movable contact member 47 carries a contact 33, and a contact 35 is secured to the arcing contact member 55. These contacts 33 and 35 are adapted to engage respectively fixed contacts 39 and 37 secured on a conductor 41 which is in turn secured to the base 11 by means of bolts 43. The conductor 41 extends upwardly and is bent at right angles, the bent portion extending through an opening in the base 11 to form a terminal connector 45.

A spring 53 compressed between a spring seat on the contact arm 30 and a spring seat on the main contact member 47 provides contact pressure for the main contacts 33-39 when the contact arm is in the closed position. Contact pressure for the arcing contacts 35-37 is provided by a spring 63 surrounding a rod 61 pivotally connected to the arcing contact member 55 and slidable through an opening in a spring seat on the contact arm 30. The spring 63 is compressed between a washer 65 seated on a shoulder on the rod 61 and the spring seat on the contact arm 30. The rod 61 has a nut 75 on the outer end thereof which acts to limit counterclockwise rotation of the arcing contact member 55 about its pivot when the contact arm 30 is moved to open the contacts. Counterclockwise movement of the main contact member 47 is limited by a projection 73 thereon striking the body of the contact arm 30. The adjustment of the nut 75 on the rod 61 is such that the arcing contacts 35-37 open shortly after the main contacts 33-39 open.

When the contact arm 30 is operated to open the contacts, the arc across the arcing contacts 35-37 resulting from the rupture of the current is drawn into an arc extinguisher indicated generally at 76 where it is cooled and extinguished. Any suitable arc extinguisher may be employed, the one illustrated comprising, generally, a stack of slotted plates disposed adjacent the paths of travel of each of the arcing contacts 35. The plates serve to draw the arc towards the ends of the slots where it is broken up into a plurality of short arcs which are quickly cooled and extinguished.

The movable arcing contact member 55 is connected by a flexible shunt conductor 77 to the main contact member 47 and another flexible

shunt conductor 79 connects the main contact member 47 to the connector 27. The connector 27 for the center pole is secured to the cross member 19 of the frame 16 by the bolts 23, and the connectors 27 for the outer poles are bolted to the base 11 with a spacer (not shown) between the base and each of the connectors in order to align the members 27 of the outer poles with the corresponding members 27 for the center pole. A conductor 81, secured to the connector 27 by means of bolts 74 extends downwardly therefrom and is bent at right angles. The horizontally disposed portion of the conductor extends between the legs of a U-shaped tripping magnet core 161 and projects through an opening in the base 11 where it forms a terminal connector 83 which, together with the terminal connector 45, serves to connect the breaker in an electrical circuit.

The electrical circuits for the several poles of the breaker are essentially the same, therefore, only the circuit for the center pole will be traced. This circuit extends from the terminal connector 45 through the conductor 41, the main contacts 33-39, the main contact member 47, the flexible shunt conductor 79, the connector 27, the conductor 81 to the terminal connector 83. The circuit for the arcing contacts 35-37 extends from the terminal connector 45, through the conductor 41, the arcing contacts 35-37, the flexible shunt conductor 77, the main contact members 47 and through the previously described circuit to the terminal connector 83.

The contact arm 30 for the center pole is biased in a clockwise or opening direction by means of a pair of springs 85 (only one being shown). These springs are tensioned between the contact arm 30 and a fixed pivot 87 supported in the main frame 16. In the closed position of the breaker, the center pole contact arm 30 and consequently all of the contact arms are releasably restrained in closed contact position (Fig. 2) by means of a toggle and linkage mechanism which is collapsible to cause opening of the contacts. The toggle and linkage forms a part of the common operating mechanism.

This collapsible linkage includes a lever 89 pivotally mounted on a fixed pivot 91 supported on the main frame 16. The lever 89 comprises a pair of levers rigidly connected by an integral cross bar 117, and is operatively connected to the support arms 31 of the center pole contact arm 30 by a main operating toggle comprising toggle links 93 and 95. The toggle link 93 has one end pivoted on a pin 101 supported on the lever 89 and the link 95 is pivoted on a pivot pin 99 on the arm 31. The links 93 and 95 are pivotally connected by a knee pivot pin 97. The toggle link 95 comprises a pair of links rigidly connected by means of an integral cross bar 115.

The free end of the lever 89 is connected by means of a link 103 to one arm of a lever 105 pivoted on the fixed pivot 87. The other arm of the lever 105 is pivotally connected to a toggle link 107 of a tripping toggle comprising the link 107 and a toggle link 109. The link 109 is pivoted on a fixed pivot 113 supported on the frame 16 and comprises a pair of links joined near the pivot 113 by a yoke 123 provided with projections 125 and 127. The toggle link 107 comprises a pair of links connected by a yoke 119 having a bent portion to which is secured an extension 121 of insulating material. The toggle links 107 and 109 are pivotally connected by a knee pivot pin 111. The purpose of the extension 121 is to co-

operate with a part connected to a manually operable handle 141 to manually trip the breaker in a manner to be more fully described later. The lever 105 and the link 103 each comprise a pair of members rigidly connected by yokes substantially as illustrated.

The linkage just described serves to releasably hold the contact assemblage including the movable contacts for all of the poles of the breaker in closed contact position. In the closed position, the main operating toggle 93-95 is overcenter above a line through the center of the pins 99-101, and a second toggle, one link of which comprises the overcenter links 93-95 and the other link of which comprises the lever 89, is overcenter above a line through the center of the pins 99 and 91. The overcenter movement of the main operating toggle 93-95 is limited by the projecting end of the link 93 engaging the cross bar 115 of the link 95.

With the main operating toggle 93-95 and the toggle comprising the links 93-95 and the lever 89 in the overcenter position, as shown in Figure 2, the springs 85 bias the lever 89 in a clockwise direction. Movement of the lever 89, however, is normally prevented by the tripping toggle 107-109 which is overcenter to the left of a line through the center of the fixed pivot 113 and the point of connection of the toggle link 107 with the lever 105. The toggle 107-109 is biased to its overcenter position by a spring 128 tensioned between the yoke 119 and the fixed pivot 113. The overcenter position of the tripping toggle 107-109 is adjustably determined by the projection 125 of the yoke 123 engaging an adjusting screw 129 in the cross member 25 of the frame. The tripping toggle 107-109 in its overcenter position, acting through the lever 105 and the link 103, prevents clockwise movement of the lever 89 and consequently holds the movable contact assemblage in the closed contact position against the biasing influence of the springs 85.

The tripping toggle 107-109 is adapted to be moved overcenter outwardly in a direction to cause its collapse to effect opening of the contacts by means of an overload trip device indicated generally at 133 (Figs. 1, 2 and 4). The overload trip device is operable in response to overload currents in the circuits of the breaker to actuate a trip rod 135 and cause collapse of the tripping toggle 107-109. The trip rod 135 is slideable vertically through a shunt trip coil (not shown) enclosed in a casing 138 attached to the main frame 16. The shunt coil is adapted to be energized from a suitable source and in a manner well known in the art, to operate the trip rod and trip the breaker from a remote point.

When operated either by the shunt coil or by the trip device 133, the trip rod 135 is thrust upwardly and strikes the projection 127 of the yoke 123 and rocks the toggle link 109 clockwise about the fixed pivot 113. This movement of the link 109 causes collapse of the tripping toggle 107-109 permitting clockwise movement of the lever 89 which permits the springs 85 to rock the movable contact assemblage clockwise to open the contacts.

The main operating toggle 93-95 does not immediately collapse but the force of the springs 85 applied through the contact arm 30-31 and the main operating toggle causes collapse of the toggle comprising the links 93-95 and the lever 89 which results in clockwise movement of the lever 89. This movement is transmitted through the link 103 and the lever 105 to complete the collapse of the tripping toggle 107-109.

The clockwise or opening movement of the contact arm 30 is arrested by projections (not shown) thereon striking portions 137 of the frame members 17 of the main frame 16. At this time the rebound of the inertia of the main operating toggle 93-95 and the parts of the linkage 89, 103 and 105 starts the main operating toggle overcenter in a direction to cause its collapse. By the time the knee pin 97 of the toggle has passed overcenter below the line 99-101 the weight of the parts act to complete the collapse of the toggle 93-95 and causes the linkage 89, 103, 105 and the tripping toggle 107-109 to be automatically reset to their normal position. The main operating toggle 93-95 remains in collapsed condition until the contacts are reclosed.

The contacts are closed manually by operation of the previously mentioned handle 141. The handle is rotatably mounted in a bracket 143 of insulating material secured to the outer end of the main frame 16. Operatively connected to the mechanism (not shown) operated by the handle is a link 151. The lower end of the link 151 is recessed and straddles a pulley-shaped roller 153 rotatably mounted on a cross member 147 rigidly connecting the outer ends of a pair of spaced contact closing levers 145. These levers are disposed on the outside of the frame 16 and are pivotally supported on the ends of the fixed pivot 91 which project beyond the frame members 17. The inner ends of the lever 145 are rigidly connected by a cross member 149. Spaced projections 152 extending from the center portion of the cross member 149 support a pivot pin 157 upon which is rotatably mounted a roller 155.

The contacts are closed manually by clockwise rotation of the handle 141. This movement of the handle, through connections (not shown) thrusts the link 151 downwardly and due to its engagement with the roller 153, rotates the closing lever 145 in a clockwise direction. During this movement of the lever 145, the roller 155 engages the link 93 of the now collapsed main operating toggle 93-95 and moves this toggle to its overcenter position. Since at this time the tripping toggle 107-109 has been restored to its overcenter position, rotation of the lever 89 is prevented and consequently the force applied by the roller 155 to straighten the toggle 93-95 rotates the contact arm 30 counterclockwise to close the contacts and to tension the springs 85. The clockwise movement of the closing lever 145 moves the toggle 93-95 overcenter above the line 99-101 so that the contacts are held in the closed position until the breaker is again tripped.

Upon release of the handle 141 following a contact closing operation, a spring 159 tensioned between the closing lever 145 and the frame 16 restores the lever 145 in a counterclockwise direction. This movement of the lever 145 and the roller 153 thrusts the link 151 upwardly to restore the handle 141 to its neutral position.

The closing lever 145 may be operated to automatically close the contacts through the agency of a motor 139 (Fig. 2) mounted on a plate attached to the side of the frame 16. The motor 139 may be energized from any suitable source. When energized, the motor is adapted, through a suitable driving connection, to rotate a crank disc 130. This disc carries an anti-friction roller 131 which engages a cam face 132 on an arm 134 secured to one side of the closing lever and rotates the arm and the closing lever 145 clockwise to effect closing of the contacts in the previously described manner. As soon as the roller 131

passes out of engagement with the arm 134, the spring 159 acts to restore the lever 145 to its normal position. The motor 139 is deenergized by a suitable limit switch (not shown).

The circuit breaker may be tripped manually by rotation of the handle 141 through a small angle in a counterclockwise direction from its neutral position. When the handle is rotated in tripping direction, a projection (not shown) on the link 151 engages the extension 121 on the yoke 119 of the toggle link 107 and rocks the link counterclockwise about its point of connection with the lever 105. This moves the tripping toggle 107—109 overcenter in a direction to cause its collapse and effects opening of the contacts in the previously described manner.

As previously stated, the trip rod 135 is operated to effect tripping of the breaker by means of a current responsive trip device 133. There is a trip device 133 provided for at least two of the poles of the breaker but since the trip devices are alike only the one for the center pole will be described.

The trip device includes the U-shaped magnet core 161 and a frame comprising substantially parallel side members 163 rigidly connected at their outer ends by a yoke 165. The members 163 are provided with mounting feet 167, and bolts 169 extend through openings in the feet 167 and in the magnet core 161 and in the base 11 to rigidly secure the core and frame to the base. A trip lever 173 is pivotally supported on a pivot 175 mounted in the frame 163. The trip lever 173 comprises a pair of spaced levers having an armature 179 secured to one end and being rigidly connected by a yoke 177 at the other end. The trip lever 173 is biased against operation by the magnet 161 by means of a pair of springs 191 (Figs. 2, 3 and 4) having one end secured to the yoke 177 and the other end attached to a vertically movable plate 193. The plate 193 cooperates with an adjusting screw 195 which is provided with a knurled head 197 bearing against the bottom side of a formed projection 199 of the yoke 165. Rotation of the screw 195 moves the plate 193 and thereby adjusts the tension of the spring 191 to vary the tripping load of the breaker. A scale plate 203, supported on spaced projections 201 of the yoke 165, bears indicia indicating the adjustment of the spring 191 or the tripping point of the breaker. An adjustable stop screw 205 provided with a lock nut 207 determines the open air gap of the magnet.

A trip bar 187 is rotatably supported in a bracket 189 secured to the casing 138 for the shunt coil. The trip bar extends across all of the poles of the breaker and is provided with an arm 185 for each pole, the center one of the arms being in alignment with the lower end of the trip rod 135. An adjusting screw 181 is mounted in each of the yokes 177 in alignment with the corresponding arm 185.

Normal rated current flowing through the circuit of the breaker, including the conductor 81, causes slight energization of the magnet 161 but not sufficient to overcome the tension of the springs 191. Upon the occurrence of an overload current above a predetermined value in the circuit of any pole, the flow of current through the conductor 81 causes energization of the magnet sufficient to overcome the spring 191 and attract the armature 179 rocking the trip lever 173 counterclockwise. At this movement of the trip lever 173, the screw 181 rotates the arm 185 and the trip bar 187 in a clockwise direction and thrusts the

trip rod 135 upwardly to trip the breaker in the previously described manner.

The construction of the circuit breaker as thus far described with the exception of the trip device 133 is essentially the same as that fully disclosed in the copending application of John W. May and Ture Lindstrom Serial No. 391,625, filed May 3, 1941, assigned to the assignee of this invention.

10 In addition to tripping the breaker in response to overload currents, it is desired also to trip the breaker when the voltage in the circuit controlled by the breaker drops below a predetermined value. For this purpose, an undervoltage trip device and an undervoltage trip mechanism are provided.

The undervoltage trip device includes an electromagnet 209 (Figs. 1, 3 and 4) comprising a U-shaped core 211 mounted between the legs of 20 a U-shaped frame 213 secured to the base 11 by screws 215, and an armature 219. Each of the two legs of the magnet core 211 is surrounded by a coil 217 which are connected in series relation and connected across the circuit of the breaker. 25 The armature 219 is mounted between a pair of spaced arms 221 pivotally supported on a pivot pin 223 mounted on the U-shaped frame 213. The undervoltage trip mechanism includes a trip member or lever 225 comprising a pair of levers pivotally supported on a pivot 227 which is mounted on the U-shaped frame 213. The levers 225 are rigidly connected at their outer ends by a yoke 229. The trip lever 225 is operatively connected to the armature 219 of the trip-magnet by means of a pair of links 231 (see also Fig. 5). 30 Each link 231 is pivoted on a stud 233 projecting outwardly from the corresponding lever 225. The links are bent inwardly (Fig. 5) and are pivotally connected by means of a pin 234 to the stem 235 of a T-shaped member having its cross member 237 secured to the arms 221 of the armature.

The yoke 229 extends toward the right (Fig. 4) and has an adjusting screw 239 secured therein by means of a lock nut 241. The screw 239 is in 45 alignment with an arm 243 similar to the arms 185 secured to the trip bar 187 so that upon counterclockwise movement of the undervoltage trip lever 225, the screw rocks the trip bar clockwise to trip the breaker as previously described.

50 The trip lever 225 is connected by a resilient linkage 245 to an arm 247 supported on a pivot 249 which is supported in a U-shaped bracket 251 secured to the underside of a horizontally disposed bar 253. This bar has a vertically extending end 255 which is secured to a large U-shaped bracket 257 mounted on the base 11 by means of screws 259.

The resilient linkage 245 forms a part of the trip mechanism and includes a cylinder 261 (Figs. 60 1, 3, 4 and 6) pivotally connected to the trip lever 225 by a pin 263 extending transversely through openings in the levers 225 and openings in the walls of the cylinder. A cylindrical sleeve 265 (Fig. 6) fitting in the end of the cylinder 261 65 which is connected to the trip lever 225, is held in place by the pin 263 extending transversely through openings therein. A shouldered rod 267 pivotally connected to the arm 247 by a pin 269 projects into the cylinder 261 and has a screw 271 70 (Fig. 6) in the end thereof. The head of the screw 271 is slidable in the sleeve 265. A spring 273 is compressed between a washer 275 seated against the inner end of the sleeve 265, and a washer 277 seated against an inner shoulder of the cylinder 261. The construction is such that

the head of the screw 271 engages the washer 275 and the shoulder on the rod 267 engages the washer 277, so that the compression of the spring 273 will be increased when the rod 267 and the cylinder 261 are moved relatively to each other in either direction.

The arm 247 is rigidly connected by a yoke 279 to a short arm 281, pivoted on the pivot 249 and secured to a vertically extending arm 283 also pivotally supported on the pivot 249 adjacent one end of the bracket 251. A yoke 285 (Fig. 3) connects the arm 283 to an arm 287 pivotally supported on the pivot 249 adjacent the other end of the bracket 251. The free end of the arm 283 (Fig. 1) is operatively connected to a projection 289 on the contact arm 30 for the left-hand pole of the breaker, as viewed from the front of the breaker, by means of a link 291.

The bar 253 and the U-shaped bracket 257 constitute a support means for an auxiliary switch device the operation and purpose of which are well known in the art and which forms no part of the present invention.

A time delay device comprising an oil dash pot provides a time delay during which the voltage of the circuit may return to normal without having tripped the breaker. The time delay device includes a plate 292 (Fig. 5) to which a dash pot 293 is attached by means of a screw thread. The plate 292 is mounted on angular portions of the U-shaped frame 213 by screws 294. A piston 295 engages a headed screw 297 in the lower end of a piston rod 299 having its upper end pivotally connected to the armature 219 by means of the pin 234 and stem 235. The upper end of the rod 299 is bifurcated to straddle the stem 235 to provide a pull along the center line of the armature. A compression spring 301 is provided to restore the piston 295 to its lower position after an operation of the undervoltage trip device.

The parts of the undervoltage trip device are shown in Figure 1 in their normal position, that is, in the positions they assume when normal rated voltage is applied across the circuit controlled by the breaker. In this condition, the linkage 245 is in tension, that is the rod 267 is drawn out of the cylinder 261 giving the spring 273 a greater compression than its initial compression. The spring 273 is given an initial compression which presses the washer 275 (Fig. 6) against the sleeve 265 and the washer 277 against the end of the cylinder. The linkage 245 is said to be in compression when the rod 267 is thrust into the cylinder beyond the position shown in Fig. 6, and is in tension when a force is applied tending to separate the rod and cylinder.

As previously stated, the linkage 245 is in tension in the closed position of the breaker. The tension of the linkage 245 in this circumstance biases the trip lever 225, and by means of the links 231, biases the armature 219 in a counterclockwise direction or to an unattracted position. Normal voltage on the circuit controlled by the breaker energizes the electromagnet 217 (Figs. 1 and 4) sufficiently to hold the armature 219 in its attracted position against the biasing influence of the resilient linkage 245.

When the voltage drops below a predetermined value, for example, 50% of normal voltage, the attraction of the magnet for the armature 219 is reduced to a point where the spring 273 in the linkage 245 overcomes the magnetic pull and rocks the trip lever 225 and the armature 219 counterclockwise to the unattracted position of the armature. The counterclockwise movement

of the trip lever 225 causes the screws 239 to rock the arm 243 and the trip bar 187 clockwise. This action, as previously described, thrusts the trip rod 135 upwardly and trips the breaker causing the contacts to open as previously described. The parts are shown in Fig. 4 at the instant the undervoltage trip device has tripped the breaker but before the contacts have opened.

The clockwise movement of the contact arm 30 to open the contacts is transmitted by the link 291 (Fig. 1) to the arm 283 and rocks this arm and the arm 247 also in a clockwise direction. The resilient linkage 245 transmits the clockwise movement of the arm 247 to the trip lever 225 restoring the trip lever in a clockwise direction to normal position and through the links 231 moves the armature 219 to its attracted position. During the latter portion of this movement, the rod 267 telescopes into the cylinder 261 placing the linkage 245 in compression thereby permitting overtravel of the arms 247 and 283 without subjecting the parts to undue strain.

If the voltage on the line controlled by the breaker returns to normal before the contacts are closed manually by operation of the handle 141, or automatically through the agency of the motor 139, the undervoltage magnet 217 will be energized sufficiently to hold the armature 219 in attracted position. In this case, movement of the contact arm 30 to close the contacts causes the linkage 245 to again be placed under tension in readiness for another undervoltage tripping operation.

If, however, the contacts should be closed against an undervoltage condition in the circuit, the magnet 217 will not have sufficient pull to hold this armature 219 and the trip lever 225 against the force exerted by the spring 273 in the linkage 245. This will result in moving the trip lever 225 to immediately trip the breaker open. It can, therefore, be seen that the breaker is trip free of the handle, that is, an undervoltage circuit condition will cause the breaker to trip open irrespective of the position of the handle.

It will also be apparent from the foregoing description that the provision of the resilient linkage protects the parts from undue strain and breakage. This linkage not only provides the energy to trip the breaker upon the occurrence of a predetermined voltage drop but also transmits the force for automatically resetting the trip device upon opening movement of the contact arm 30.

The provision of the time delay device makes possible the correction of a momentary voltage drop without disrupting the circuit or service. The time delay may be omitted in which case the breaker will be tripped open instantaneously upon the occurrence of a predetermined voltage drop.

Another important feature of the undervoltage device is the absence of latch mechanisms thus providing a simple reliable and inexpensive construction.

Certain features shown and described but not claimed in this application are fully disclosed and claimed in the aforementioned copending application of John W. May and Ture Lindstrom, Serial No. 391,625, filed May 3, 1941, and assigned to the assignee of this invention.

Having described a preferred embodiment of the invention in accordance with the patent statutes, it is to be understood that various changes and modifications may be made therein without departing from some of the essential

features of the invention. It is, therefore, desired the language of the appended claims be given as reasonably broad interpretation as the prior art permits.

We claim as our invention:

1. In a circuit breaker, relatively movable contacts, operating mechanism for said contacts, trip mechanism including a resilient means connected to a part movable with the movable contact and operable to trip the circuit breaker operating mechanism, and a trip device operable in response to predetermined circuit conditions to initiate an operation of the trip mechanism, said resilient means being movable by the opening operation of the breaker to reset the trip device.

2. In a circuit breaker, relatively movable contacts, operating mechanism for said contacts, trip mechanism including a spring connected to a part movable with the movable contact and operable to trip the circuit breaker operating mechanism by energy stored in the spring by the closing movement of the breaker, and an electromagnetic trip device including an armature normally restraining the spring but operable in response to predetermined circuit conditions to permit tripping operation of the spring, said spring being moved by the opening operation of the breaker to automatically reset the armature.

3. In a circuit breaker, relatively movable contacts, operating mechanism for said contacts, a trip mechanism including a resilient linkage operable to effect tripping of said circuit breaker operating mechanism, a trip device including an electromagnetic means for restraining the trip mechanism against operation, said electromagnetic means being responsive to predetermined circuit conditions to release the trip mechanism for a tripping operation, said linkage being moved by opening movement of the breaker to reset the trip mechanism and the trip device, and a time delay device comprising a dashpot having a retarding member operatively related to the tripping mechanism to delay tripping operation thereof and resettable independently of the resetting movement of the trip mechanism and the trip device.

4. In a circuit breaker, relatively movable contacts, operating mechanism for said contacts, a releasable trip mechanism including a spring operable to effect tripping of the circuit breaker operating mechanism, and an electromagnetic trip device for normally restraining said spring in operative condition, said trip device being operable in response to predetermined circuit conditions to release the trip mechanism for operation, said spring being operable by opening movement of the contacts to reset the trip mechanism and being restored to operative condition by closing of the contacts.

5. In a circuit breaker, relative movable contacts, operating mechanism for said contacts, a trip member operable to cause opening of the contacts, a resilient linkage biasing the trip member in tripping direction at least when the contacts are closed, and an electromagnetic trip device operable in response to predetermined circuit conditions to permit said resilient linkage to move the trip member to trip the breaker, said linkage being moved by the opening movement of the breaker to reset the electromagnetic trip device and the trip member.

6. In a circuit breaker, relatively movable contacts, operating mechanism for said contacts, a trip mechanism comprising a trip member operable to cause opening of the contacts and spring

means biasing said trip member in tripping direction at least when the contacts are closed, and an electromagnetic trip device operable in response to a predetermined drop in voltage to permit said spring to operate said trip member, said spring means being operable by opening movement of the contacts to reset the trip member and the trip device.

7. In a circuit breaker, relatively movable contacts, a switch member movable to open and close said contacts, actuating mechanism for moving said switch member to open and to closed circuit positions, a trip mechanism including a spring biased to effect an opening operation of the switch member, and an electromagnet for holding the trip mechanism in operative position, said electromagnet being operable in response to predetermined circuit conditions to release the trip mechanism, and said spring being operable by the switch member when said switch member is moved to open position to restore the trip mechanism to operative position.

8. A circuit breaker comprising relatively movable contacts, operating mechanism for said contacts, means comprising a spring connected to a part movable with the movable contact, said spring being stressed when said contacts are closed and being operable to effect an operation of the operating mechanism to open the contacts, and electromagnetic means including an armature for holding said spring in stressed condition and operable in response to predetermined circuit conditions to permit operation of the spring, the movement of the movable contact to open position acting through said spring to reset the armature to holding position.

9. A circuit breaker comprising relatively movable contacts, a switch member operable to open the contacts, operating mechanism for said switch member, a trip member operable to cause opening of the contacts, a resilient linkage connecting the switch member to said trip member, said resilient linkage biasing the trip member in tripping direction at least when the contacts are closed and acting when released to operate the trip member, holding means comprising an electromagnet for releasably restraining the trip member, said electromagnet being responsive to predetermined voltage fluctuations in the circuit to release the trip member, and said resilient linkage acting to transmit the movement of the switch member when said switch member operates to open the contacts to reset the trip member.

10. In a circuit breaker, relatively movable contacts, operating mechanism for said contacts, a switch member movable to open and close the contacts, a trip member operable to cause opening of the contacts, a spring connected between a part that is moved during closing of the breaker and said trip member, said spring biasing the trip member in tripping direction at least when the contacts are closed and acting when released to operate the trip member, an electromagnet having an armature operatively connected to the trip member for restraining the trip member against the action of said spring, said electromagnet being responsive to predetermined voltage conditions in the circuit to permit the spring to operate the trip member, said spring acting to transmit the movement of the switch member when said switch member moves to open the contacts to restore the trip member to operative position.

11. In a circuit breaker, relatively movable contacts, operating means for said contacts, a trip

mechanism including a resilient linkage operable to cause tripping of said circuit breaker operating mechanism, an electromagnet including an armature opposing operation of the trip mechanism, said electromagnet being operable in response to predetermined circuit conditions to permit operation of the tripping mechanism, and means connected to said armature for delaying tripping operation of said resilient linkage for a predetermined length of time, said resilient linkage being operable independently of said delaying means upon opening of the contacts to reset the trip mechanism.

12. In a circuit breaker, relatively movable contacts, operating mechanism for said contacts, tripping mechanism including a resilient linkage operable to effect opening of the contacts, an electromagnet having an armature operatively connected to the trip mechanism for holding said trip mechanism against the action of said resilient linkage, said electromagnet being responsive to predetermined circuit conditions to permit operation of the trip mechanism, a time delay device comprising a dashpot operatively connected to the armature for opposing tripping movement of said armature to delay the operation of the trip mechanism, said resilient linkage being operable by opening movement of the contacts to reset the armature to holding position, said armature being movable relative to said dashpot when the armature is moved to reset position, and spring means for resetting said dashpot.

13. In a circuit breaker, relatively movable contacts, operating mechanism for said contacts, tripping mechanism including a resilient means operable to effect opening of the contacts, a trip device including an electromagnet having an armature operatively connected to the tripping mechanism for restraining said tripping mechanism in operative position, said electromagnet being operable in response to predetermined voltage conditions in the circuit to release the tripping mechanism for a tripping operation, a time delay device for delaying tripping operation of the tripping mechanism but which permits quick resetting of said tripping mechanism, said resilient means being operable by opening movement of the contacts to restore the tripping mechanism to operative condition, and a separate spring for restoring said time delay device to operative condition.

14. A circuit breaker comprising relatively mov-

able contacts, operating mechanism for said contacts, means comprising a spring connected to a part movable with the movable contact, said spring being in a stressed condition when the contacts are closed and being operable to effect an operation of the operating mechanism to open the contacts, and electromagnetic means including an armature for restraining said spring in stressed condition and being operable in response to predetermined circuit conditions to permit operation of the spring, the movement of the contacts to open position acting through said spring to reset the armature to restraining position and the movement of said contacts to closed position acting to stress the spring.

15. A circuit breaker comprising relatively movable contacts, a switch member movable to an open position and to a closed position to open and close the contacts, operating mechanism for said switch member, a trip member operable to effect opening movement of the switch member, means comprising a spring connecting the switch member to said trip member, said spring having energy stored therein when the switch member is in closed position and being operable to effect an opening movement of the switch member, an electromagnetic means for restraining said spring and being operable in response to predetermined circuit conditions to permit the spring to operate said trip member, the movement of the switch member to open position acting through said spring to reset the trip member and the movement of the switch member to closed position acting to store energy in the spring.

16. A circuit breaker comprising relatively movable contacts, operating mechanism for said contacts, means comprising a spring connected to a part movable with the movable contact, said spring being stressed when the contacts are closed and being operable to effect an operation of the operating mechanism to open the contacts, and electromagnetic means for holding said spring in stressed condition and operable in response to predetermined circuit conditions to permit operation of the spring, the movement of the contacts to open position acting through said spring to reset the holding means to holding position, said spring being effective to permit overtravel of the parts connected thereto.
